UNITED STATES PATENT OFFICE.

EDWARD F. BAUM, OF WORMLEYSBURG, PENNSYLVANIA.

WEATHER-INDICATING DEVICE.

Application filed November 1, 1920. Serial No. 421,203.

To all whom it may concern:

Be it known that I, EDWARD F. BAUM, a citizen of the United States, residing at Wormleysburg, in the county of Cumberland and State of Pennsylvania, have invented new and useful Improvements in Weather-Indicating Devices, of which the following is a specification.

My invention relates to that class of weather indicators in which a counter balanced oscillating needle, or pointer, reciprocating with a cord, contracting and expanding as the humidity in the atmosphere increases or diminishes, moves to and fro along a dial on which words, signs or characters indicate different phases of the weather.

The object of my invention is to provide a device for indicating impending changes in the weather several hours in advance of their occurrence, which shall be simple and economical in construction, compact in form, durable in character and operative in vertical, inclined, or horizontal positions.

I obtain the object of my invention by the device described in the following specifications and drawings in which similar letters refer to similar parts.

Figure 1 is a plan drawing with the casting J omitted. A is a base, which may be of wood or any other suitable material. B is a needle or pointer of any desirable material, hinged on the pin i, fastened on or to the base A. The needle or pointer B is counter balanced in the direction of the point f by a spiral spring S which may be attached in any desired manner, preferably, however, to a short arm projecting laterally at an angle at a point near the pivot end. C is a cord or string of cat gut, linen, or other hygroscopic material which shrinks and contracts in length in a moist atmosphere. One end of the cord C is fastened at a stationary pin e and the other end is threaded through a transverse hole t in the key K and tied or otherwise fastened. The key K turns tightly in the hole h in the base and the cord C is wound around the shank, or unwound, as it is turned to the right or left. L is a short thread or light cord attached securely to the needle B at n, a short distance above the bearing i and tied or otherwise fastened to the cord C and x. The words Clear, Change, Storm, or other words, signs or characters may be printed on, or attached to the base near the top in any other suitable manner to constitute an indicating dial D.

In assembling my device the cord C is dried until it contains but an insignificant amount of moisture. The end of the needle B is moved to the point f which would obviously stand for Clear, etc. The cord C is fastened at e and to the key K. The key K is turned so the cord C is wound taut along a deflected line from the point e to x and thence to K, and is attached to the needle B by the thread L.

The successful operation of my device is brought about by placing it where the atmosphere is unaffected by artificial heat and where the air circulates freely. If there is an appreciable amount of humidity in the atmosphere the cord C absorbs moisture and shrinks, the shrinkage varying in proportion to the humidity.

As the humidity increases the cord C continues to shrink until it is taut on a straight line from e to K as is indicated by dotted lines. As the cord straightens it pulls the needle B from the word Clear in the direction of Change and if the humidity is sufficient to presage rain or snow further on until it stands at Storm, as is also indicated in dotted lines. As the humidity diminishes the cord C dries and sags and the needle B is propelled backward along its line of transition by the spring S.

The needle B can be set and the device regulated by turning the key K.

It will be obvious that the construction of my device may be modified without departing from the mechanical principles involved. For instance, it will be understood that cat gut is a material that shrinks by the absorption of moisture. If the cord C is a string or strip of material such as cardboard that expands and sags in damp weather the words Clear and Storm may be transposed on the dial D to co-ordinate with the reversed action thereof in relation to the needle B.

A weight may be employed instead of a spring, as shown in Fig. 2, in which similar parts correspond with similar parts and are described by the similar characters employed in Fig. 1 with the exception of W which shows a weight arranged to do the work performed by the spring S in Fig. 1.

Fig. 3, shows the mechanism protected by a cover. A, represents the base. J, is a casting having therein an opening or slot O, through which the end of the pointer B may be observed in its transitions. D is a dial having on the face thereof suitable words,

- and signals f', f'', f'' , indicating changes in the weather and the regulating key K. The casing J may be of any desired material, preferably a piece of flat, or suitably formed sheet metal, which may be attached to the base A in any convenient manner to cover and protect the mechanical parts and at the same time provide for a free circulation of air.
- 10 What I claim as my invention is:
1. In a weather indicating device, a base, a dial having weather indicating characters thereon and a counter balanced pointer or needle cooperating therewith, oscillating on a fixed bearing and linked by means of a thread or cable to a string or strip of hygroscopic material, mounted in relation thereto and fastened at each end to said base, the

link and needle being actuated by the lateral movements of the hygroscopic cord or strip 20 as it relaxes or contracts when variously affected by the absorption or discharge of moisture.

2. In a weather indicating device the base A, the needle B oscillating on the pin i and 25 suitably connected by means of the link L to the cord C, fastened to the stationary pin e and the regulating key K; the counter balancing spring S, in combination with the dial D provided with indicating characters, 30 substantially as described.

EDWARD F. BAUM.
